UNITED STATES PATENT OFFICE.

FRIEDRICH HÄUSSER AND HERMANN ELLERBUSCH, OF DORTMUND, GERMANY.

METHOD OF AND APPARATUS FOR REGULATING THE FUEL SUPPLY IN INTERNAL-COMBUSTION ENGINES.

Application filed May 13, 1924, Serial No. 713,067, and in Germany July 12, 1922.

Our invention relates to a method of and apparatus for regulating the fuel supply in internal combustion engines particularly for automobiles.

5 It is an object of our invention to eliminate the drawbacks of the existing systems for injecting measured quantities of fuel which are particularly inconvenient in motor car engines, etc., on account of the small 10 quantities of fuel involved.

It further follows according to the present invention that the regulating of the fuel in engines having valve control is carried out by means of the suction. Thereby the fuel 15 will be fed according to the air pressure, which is particularly useful for heavy fuel.

We effect regulation of the fuel quantity by varying the pressure of the fuel as well as the injection period. The pressure is 20 varied in direct proportion to the load, and the injection period in inverse proportion to the speed of the fuel pump. By these means, the influence of the varying delivery with variations in the engine speed is practically 25 eliminated, since the injection period is extended if the speed of the engine, and therewith the delivery of the fuel pump and the fuel pressure, decreases, and vice versa. The 30 variable "delivery of fuel pump" being eliminated, the quantity of fuel supplied to the engine is determined by the valve gear alone. This facilitates the control of the regulation, and, besides, permits direct drive of the fuel 35 pump by the engine without any means for compensating its variable delivery.

In our novel method, the fuel delivery of the pump which is in excess of the demand of the engine, is conducted to a control valve chamber, preferably through a compensation tank or the like. The pressure in said 40 control valve chamber is regulated in proportion to the load on the engine, preferably by a needle valve which by-passes and returns to the fuel tank the excess fuel. The 45 needle valve may be adjusted directly by the speed governor of the engine, or—preferably in car engines—by the vacuum at the rear of the throttle which may be set from the outside by known means. From the control 50 valve chamber, the fuel is delivered to the cylinder or cylinders by a distributor operated by the engine. The distributor connects the cylinder or cylinders with the control valve chamber at the right time and determines the period of injection in inverse

proportion to the delivery of the fuel pump, that is, the speed of the engine.

The fuel and (or) the air for injection may be heated and the supply of air may be regulated similarly to the fuel supply.

In the drawings affixed to this specification, an apparatus for performing our novel method is illustrated diagrammatically by way of example.

In the drawings:

Fig. 1 is a plan view of a four-cylinder motor car engine fitted with my improved apparatus.

Fig. 2 is a longitudinal section of the control valve chamber.

The fuel is supposed to be atomized by compressed air in nozzles in front of the inlet valves, and to be injected with such air. The cylinders of the engine are indicated at 1, 2, 3, and 4, 5, 6, 7, and 8 being the inlet 75 valves, and 9, 10, 11, and 12 are the atomizers in which the fuel coming from the distributor 22 is atomized by compressed air generated by a fan or the like and conducted to said atomizers by a pipe 28. The usual 80 throttle 21 is provided for regulating the admission of air for combustion.

The distributor 22 comprises a casing 23, a cover 24, and a rotary disc valve 25 adapted to be rotated from the engine by 85 means not shown. Fuel is admitted to a central bore in the disc 25 from the control valve casing 26 and distributed by a radial bore 27 connected with the central bore. When the disc valve 25 rotates, openings 17, 90 18, 19, and 20 in the cover are connected with the control valve chamber 26 in succession through the medium of bore 27. The openings in the cover 24 are connected with the cylinders 1, 2, 3, and 4 by the pipes 13, 14, 95 15, and 16.

Fuel is supplied to the control valve chamber 26 by a fuel pump, not shown, through a pipe 29. The fuel is supplied in excess of the demand of the engine. Fuel pressure in 100 the chamber 26 is regulated by a piston 32 in a chamber 30 connected with the suction manifold at some point to the rear of the throttle 21, by a pipe 31. The piston is loaded by a spring 33. Secured to the base 105 of the piston 32 is a needle valve 34 which cooperates with a restricted seat 35 in the chamber 26 and allows a certain percentage of the fuel supplied in excess to the chamber 26 to escape into a chamber 36 and to re- 110

turn to the fuel tank through a pipe 37. By suitably dimensioning the parts, the needle valve may be caused to supply only the quantity of fuel required in the engine at the existing load.

5 The influence of the variable delivery of the fuel pump is made up for by the distributor 22 whose speed varies with the speed of the pump, so that the periods for which 10 the atomizers 9, 10, 11, and 12 are connected with the control valve chamber 26, are varied inversely to the delivery of the pump.

It will be understood that the quantity of fuel supplied is regulated by the period 15 of flow and by the position of the needle valve 34 which is adjusted in accordance with the vacuum at the rear of the throttle 21, that is, in proportion to the weight of air in the engine.

20 This avoids overfeeding and its consequences which are particularly undesirable in heavy oil engines.

Our method may also be applied to the case in which the fuel nozzles are arranged 25 in the combustion chamber or chambers of the engine instead of being arranged in the suction manifold.

We claim:—

1. An apparatus for regulating the fuel 30 supply in internal combustion engines particularly for automobiles, comprising a control valve chamber adapted to have fuel supplied to it under pressure; a rotary distributor which is in communication with the control valve chamber, said distributor being adapted to distribute the fuel to the cylinders of the engine; a regulating chamber; and a piston in said regulating chamber having a needle valve therein which projects into the control valve chamber, said piston being controlled by the suction of the engine.

2. An apparatus for regulating the fuel supply in internal combustion engines particularly for automobiles, comprising a control valve chamber adapted to have fuel supplied to it under pressure by a pump driven by the engine, a rotary distributor adapted to distribute the fuel to the cylinders of the engine and being in communication with the control valve chamber, said distributor being driven by the engine; and a fuel regulator adapted to control the valve in said chamber, said regulator being controlled by the suction of the engine.

3. An apparatus for regulating the fuel supply in internal combustion engines particularly for automobiles, comprising a control valve chamber adapted to have fuel supplied to it; a rotary distributor which

is in communication with the control valve chamber, said distributor being adapted to distribute the fuel to the cylinders of the engine; and a piston having a needle valve thereon which projects into the control valve 65 chamber, said piston being controlled by the suction of the engine.

4. An apparatus for regulating the fuel supply in internal combustion engines particularly for automobiles comprising a control valve chamber adapted to have fuel supplied to it; a rotary distributor having a bore therein which is in communication with the control valve chamber, said distributor being adapted to distribute the fuel 70 to the cylinders of the engine by means of said bore; a regulating chamber for the fuel; and a piston in said regulating chamber having a needle valve thereon which projects into the control valve chamber, said piston being actuated by the suction of the engine.

5. An apparatus for regulating the fuel supply in internal combustion engines particularly for automobiles comprising a control valve chamber adapted to have fuel supplied to it under pressure and in excess 85 of demand; a rotary distributor adapted to distribute the fuel to the cylinders of the engine and being in communication with the control valve chamber; a regulating chamber for the fuel and being in communication with the intake of the engine; and a piston and needle valve in said regulating chamber, said needle valve projecting into 90 the control valve chamber in order to regulate the fuel, said piston being actuated by the suction of the engine.

6. An apparatus for regulating the fuel supply in internal combustion engines particularly for automobiles, comprising a control valve chamber adapted to have fuel supplied to it under pressure by a pump driven by the engine, said chamber having a valve therein which is adapted to regulate the quantity of fuel conducted to the cylinder and to return the excess fuel; a rotary distributor adapted to distribute the fuel to the cylinders of the engine and being in communication with the control valve chamber, said distributor being driven by the engine; and a fuel regulator adapted to control the valve in said chamber, said regulator being controlled by the suction of the engine.

In testimony whereof we have affixed our signatures.
